[57] CLAIM

The ornamental design for a recreational vehicle refrigerator door latch or similar article, substantially as shown and described.

DESCRIPTION

FIG. 1 is an isometric view of a recreational vehicle refrigerator door latch or similar article showing my new design;

FIG. 2 is a bottom view, drawn to an enlarged scale, of the door latch;

FIG. 3 is an elevation of one side of the door latch;

FIG. 4 is a top view of the door latch;

FIG. 5 is another side elevation of the door latch, showing the side opposite to that illustrated in FIG. 3;

FIG. 6 is a rear elevation of the door latch; and

FIG. 7 is a front elevation of the door latch.

The broken lines shown in FIG. 1 are for illustrative purposes only.

FIG. 1
